UNITED STATES PATENT OFFICE.

FREDERICK D. OSTERHOUDT, OF RENTON, WASHINGTON, ASSIGNOR OF ONE-THIRD
TO DOUGLAS LEWIS AND ONE-THIRD TO GEORGE H. WILLIAMS, OF RENTON,
WASHINGTON.

SPOOL-HOLDER.

No. 892,077.

Specification of Letters Patent.

Patented June 30, 1908.

Application filed September 17, 1907. Serial No. 393,392.

To all whom it may concern:

Be it known that I, FREDERICK D. OSTERHOUDT, a citizen of the United States, residing at Renton, in the county of King and State of Washington, have invented certain new and useful Improvements in Spool-Holders, of which the following is a specification, reference being had therein to the accompanying drawings.

10 This invention relates to holders for thimbles and spools of thread; and has for its object the provision of a device of this nature which will be of inexpensive construction, and exceedingly convenient in use.

15 With these ends in view the invention consists in the novel construction, adaptation and combination of parts, as will be herein-after described and claimed.

In the drawings, Figure 1 is a front elevation; Fig. 2 is a rear elevation; and Fig. 3 is a vertical sectional view of devices embodying my invention. Fig. 4 is a perspective view of the same with a spool and thimble supported thereby.

20 The holder is comprised of a plate 5 of a substantially rectilinear configuration and having intermediate its ends, two oppositely disposed wings 6 which are bent so as to protrude forwardly. These wings are apertured, 25 as at 7, to provide bearings for the reduced extremities 8' of an arbor 8 which carries the spool 9 and such arbor has its ends engaged by the wings through spreading the latter to introduce the arbor and then releasing the 30 wings to resume their normal position.

35 In the upper edge of each of the wings, and in proximity of their forward ends, is a triangular shaped notch 10, having its edges 40 filed or otherwise formed to present sharp cutting edges for severing the thread when drawn thereagainst.

45 Adjacent of the lower end of the plate the same is provided with a plurality of perforations 11 wherethrough is successively passed the thread-end 9' for the purpose of creating a resistance to the withdrawal of the thread from the spool and also retaining the extremity within convenient reach of the user. At 50 the back of said plate and near its top is a safety-pin 12 whereby the holder may be secured to a woman's garment. This pin can be secured to the plate in any reliable manner,

but desirably by stamping out portions 13 of the plate to afford eyes 13' wherein the pin-shank 12' is held.

55 A ring 14 for the reception of a thimble 15 is secured to the plate somewhat above the wings, and, most conveniently, by making the same of a band which is centrally looped to form the ring and has its extremities extended through an incision 16 of the plate and thence turned in opposite directions, as at 14', upon the rear face of the plate.

60 17 is a hole whereby the device may be suspended when unemployed.

65 Assuming that the thimble and spool are respectively supported by the ring and arbor, and that the end of the thread has been passed to and fro through the perforations 11, as already described and the device then 70 secured to a person's waist-garment by the aforesaid safety-pin, the thread can then be readily withdrawn to a desired length and cut off by drawing it sharply into a notch 10 of a wing. The thimble is within convenient reach for use and after the needle has been threaded sewing can be proceeded with. As often as the thread becomes exhausted another length may be taken from the spool and severed and without loss of time and annoyance had where the spool is required to be sought for at each successive demand for 75 a length of thread.

80 An advantage of this invention resides in its availability for those who use a continuous thread in their work, as in knitting or crocheting, the device securing the spool or ball of material to the user's dress and preventing its loss when moving about. It 85 can obviously be made in sizes to suit the character of work required and its simple construction allows of its manufacture at a low cost.

85 Having described my invention, what I claim is—

90 1. A holder of the class described comprising a plate formed intermediate the ends of its longitudinal edges with forwardly-extending wings having notches in their upper edges, said notches provided with sharp 95 cutting edges, and said wings having apertures wherethrough to receive a spool-carrying spindle, said plate being provided adjacent its lower end with a plurality of aper-

tures disposed one above the other through which the thread from the spool carried on said spindle is passed.

2. A holder of the class described, comprising a rectangular plate provided intermediate the ends of its longitudinal edges with forwardly-extending wings having apertures therethrough to receive a spool carrying spindle, said plate provided adjacent its lower end with a plurality of apertures disposed one above the other through which

apertures the thread on the spool is passed, lugs struck out from the rear face of said plate and a fastening device carried by said lugs.

In testimony whereof I affix my signature in presence of two witnesses.

FREDERICK D. OSTERHOUDT.
